ELISHA E. EVERITT, OF PHILADELPHIA, PENNSYLVANIA.

Letters Patent No. 69,198, dated September 24, 1867.

IMPROVED SPRING-BED BOTTOM.

The Schedule referred to in these Letters Patent and making part of the same.

TO ALL WHOM IT MAY CONCERN:

Be it known that I, ELISHA E. EVERITT, of Philadelphia, Pennsylvania, have invented an improvement in Spring-Bottoms for Bedsteads; and I do hereby declare the following to be a full, clear, and exact description of the same.

My invention consists of certain improvements in that class of spring-bottoms for bedsteads which consist of elastic wooden slats, supported at each end on springs attached to transverse bars secured to a bedstead; and my improvements, which are fully described hereafter, have for their object the ready detachment of the several parts, for cleansing, &c., and the prevention of the creaking noise which is common to ordinary spring-bottoms.

In order to enable others skilled in the art to make and apply my invention, I will now proceed to describe its construction and operation, reference being had to the accompanying drawing, which forms a part of this specification, and in which—

Figure 1 is a vertical section of the frame of the bedstead with my improvements.

Figure 2 an enlarged view of part of fig. 1.

Figure 3 a section on the line 1-2, fig. 2.

Figure 4 a plan view.

Figure 5 a perspective view of one of the sockets for receiving the ends of the transverse bars, and

Figure 6 a modification of my improvement.

A and A' represent the end bars, and B one of the side bars of a bedstead, and to the inside of the said side bars are secured the cast-iron sockets C, fig. 5, for receiving the ends of the transverse bars D; each of which has, both on its upper and under edge, longitudinal concave grooves *a*, adapted to the enlarged portions *f* of a series of pins E. Round each projection *e* of each pin is coiled the portion *b* of a wire spring, the termination of each coil being the straight wire *d*, which fits snugly in but so as to be easily withdrawn from a hole in the transverse bar D. From the two coils the wires take an inclined direction, as shown at *g*, fig. 2, and are united by and form a part of the transverse portion *h* of the wire, on which rests the slat F; pins *i i*, projecting one from each end of the latter, passing through the hook (fig. 2) formed at the bend *x*, where the inclined portions *g* of the wires meet the horizontal portion *h*. Owing to the peculiar form of the springs, the slats F can be readily introduced into their places, in which they are retained vertically by the pins *i i*, and laterally by the heads *x*. The projections *e* of the pins E are so much smaller than the portion *f*, that the coiled portions *b* of the wire spring are free from contact with the groove of the transverse bar D, hence the friction of the spring against the bar, and the creaking noise accompanying such friction, are prevented. By the pressure of the slats against the springs, the transverse bars are apt to be warped by being bent outwards in the direction of the arrow, fig. 4, or downwards. A quick remedy is afforded for this by withdrawing the straight portions *d d* of the springs from the said bars, reversing the same, or turning them upside down, according to the direction in which they have been warped by the above-mentioned pressure on the slats, the enlarged portions *f* of the pins fitting snugly in any of the grooves of the transverse bars. In fig. 1 the slats rest on and are confined to springs at both ends; but in fig. 6, the ends of the slats nearest the foot of the bedstead fit over pins *g* on the transverse bar D' on which the slats rest. This is a somewhat cheaper application of my invention than that shown in fig. 1, and may be adopted in cases where most elasticity is required at and near the head of the bed. The cast-iron sockets used for receiving the end of the transverse bars will be readily understood on reference to fig. 5, the back of each socket being provided with somewhat sharp projections *m*, which penetrate the wood when the socket is driven against the inside of the longitudinal bar of the bedstead, and serve to resist the strain imparted to the transverse slats, the sockets being further secured by light wood-screws passing through lugs *n n*.

It will be seen that the slats are at liberty to slide freely to and fro on the spring as the latter yields, that they can be readily connected to the spring by depressing the latter until the pins *i i* are in the position shown by dotted lines *t t*, fig. 4, and that the springs themselves can be readily connected to and disconnected from the transverse bars without the aid of any fastenings which require tedious manipulation.

I claim as my invention and desire to secure by Letters Patent—

1. The transverse bars D, having one or more grooves in combination with the pin E, arranged to receive the coils of the spring, and to fit the said groove, all substantially as set forth.

2. The within-described spring, having ends *d d* fitting into the transverse bars D, and being bent and arranged for the reception of the slats and pins *i i*, substantially as set forth.

3. The slats, connected at one end to the within-described springs on the transverse bar D, and resting at the opposite end on the transverse bar D', to which it is confined by a pin, *y*, all as set forth.

In testimony whereof I have signed my name to this specification in the presence of two subscribing witnesses.
